UNITED STATES PATENT OFFICE.

HARRY W. KELSEY AND WILLIAM H. BAER, OF MIDDLETOWN, CONNECTICUT, ASSIGNORS TO THE RUSSELL MANUFACTURING COMPANY, OF MIDDLE-TOWN, CONNECTICUT.

DESIGN FOR A BOX COVER.

61,308.

Specification for Design.

Patented Aug. 1, 1922.

Application filed September 26, 1921. Serial No. 503,394. Term of patent 14 years.

To all whom it may concern:

Be it known that we, HARRY W. KELSEY and WILLIAM H. BAER, citizens of the United States, residing at Middletown, in the county of Middlesex and State of Connecticut, have invented a new, original, and ornamental Design for a Box Cover, of which the following is a specification, reference being had to the accompanying drawing, forming part thereof.

The figure is a perspective view of a box cover, showing our new design.

We claim:

The ornamental design for a box cover, as shown.

HARRY W. KELSEY.
WILLIAM H. BAER.

Witnesses:

CHANNING E. HARWOOD,
C. C. LYMAN.
